G. W. PERKINS

STAPLING MACHINE

Filed June 15, 1922

INVENTOR:

George W. Perkins

by Macleod, Culver, Copeland & Dible

Attys.

UNITED STATES PATENT OFFICE.

GEORGE W. PERKINS, OF BOSTON, MASSACHUSETTS, ASSIGNOR TO HEATON PENINSULAR BUTTON FASTENER COMPANY, OF BOSTON, MASSACHUSETTS, A CORPORATION OF MAINE.

STAPLING MACHINE.

Application filed June 15, 1922. Serial No. 568,505.

To all whom it may concern:

Be it known that I, GEORGE W. PERKINS, a citizen of the United States, residing at Boston, county of Suffolk, State of Massachusetts, have invented a certain new and useful Improvement in Stapling Machines, of which the following is a specification, reference being had therein to the accompanying drawings.

- 10 The invention relates to a machine for making metallic fasteners for fastening buckles, buttons, or other devices to shoes or other sheet material, in which a blank for the fastener is cut from a length of wire and is then bent to form a staple, which is then driven through the article to which the button or buckle is to be attached and clinched to fasten the button or buckle to the article. One form of mechanism for doing this is shown in Patent No. 982,440, granted to me February 24, 1911, in which the wire is fed through a guide to a position above an arbor and beneath a reciprocable slide formed with legs, which when 25 the slide moves downward bend the blank over the arbor to form the legs of the staple, a blank of suitable length for the staple being cut from a length of wire after it is fed over the arbor before the staple former 30 descends, the arbor being withdrawn after the staple is formed to allow the slide to carry the staple to a position where a member mounted on the slide drives the staple through the article to which the button or buckle is to be attached, said article having been previously placed upon an anvil.
- In the device shown in said Patent, No. 982,440, one of the cutters is stationary and the other is slightly movable up and down 40 but is not attached to the slide nor is it actuated by the slide or former.

In an application, filed January 3, 1922, Serial No. 526,501, which is especially intended for fastening buckles to shoes or other articles of sheet material, the movable cutter is rigidly connected with the slide so that after the staple is formed the cutter moves down with the slide and former during the operation of carrying and driving 45 the staple. It is important in this class of machines, shown in both my previous patent and said patent application, that the said legs of the slide which bend the legs of the staple shall also be utilized when the

slide moves downward to clamp against the anvil the article to which the buckle or buttons are to be attached, while the staple is being driven by the driver. When the cutter is attached to the slide, as in my said patent application, No. 526,501, the cutter 55 is apt to engage with some portion of the buckle or other obstruction before the legs of the slide have descended far enough to clamp the article to the anvil. This cannot be remedied by having the legs of the slide 60 extend further below the lower edge of the cutter, because in that case the engagement of the legs with the wire to bend it over the arbor will not be properly timed with relation to the cutting of the wire, because the 65 wire would be bent before it would be cut. I desire, however, to have the cutter actuated by the movement of the former so as to have a perfectly timed operation of the 70 cutter.

The object of the present invention is to mount the cutter separate from the slide and former and to provide means whereby when the slide moves down and has arrived at a suitable predetermined position the cutter 75 may be actuated by the slide to sever the wire blank from the body of the wire and be in position not to interfere with the movement of the slide to clamp the article to the anvil.

The invention will be fully understood from the following description when taken in connection with the accompanying drawings, and the novel features thereof will be pointed out and clearly defined in the claims 80 at the close of this specification.

In the drawings, Fig. 1 is a front elevation partly in section of a machine embodying the invention.

Fig. 2 is a side elevation partly in section 85 of the machine shown in Figure 1, showing the parts in position before the slide has descended to actuate the cutter to cut the wire.

Fig. 3 is a side elevation partly in section showing the slide and cutter in the position 100 after the wire has been severed.

Fig. 4 is a detail view of the cutter.

Referring now to the drawings, A represents the head of the machine which contains the staple forming and wire feeding 105 mechanism, and B represents the base on which is mounted the anvil.

Preferably the blank from which the sta-

2
ples are formed is cut from a wire which is fed to the forming mechanism intermittently as the staples are severally needed. Any suitable wire feeding mechanism may be employed. That shown in the drawings is very similar to that shown in my said prior Patent, No. 982,440, and said pending application, Serial No. 526,501. In brief, a length of wire 5 may be run from a reel or any other suitable source of supply. Mounted fast on a rod 6 is a block 7, which is termed the wire end block, and passing loosely through said block 7 is a rod 8 which serves as a guide. The wire 5 passes between a rest 9 pivoted to the block 7 and a dog 10 pivoted to the block 7, whose operation will be well understood, said dog permitting the forward feed of the wire but preventing the backward slipping of the wire.

in Figure 2. The slide 18 is movable in a vertical direction and the arbor 25 is movable in a horizontal direction in a guide 42 in the head of the machine. The forward portion of the arbor is formed with a cam surface 43. When the slide 18 has moved down far enough to form the legs of the staple, its lower end will engage the said cam surface 43 and move the arbor to the right, viewing it as in Figure 2, thus withdrawing the arbor from the path of movement of the former. A spring 44 normally holds the arbor in a forward position to support the wire blank ready for the forming operation of the staple, but yields to the action of the slide on the cam surface 43 of the arbor to permit the withdrawal of the arbor, and the spring is thereby compressed ready to throw the arbor forward again into operative position 20 at the proper time.

What I claim is:

1. In a machine of the character described, an arbor, a wire guide adjacent the arbor through which wire is fed to lay upon the arbor a projecting portion of the wire, the forward end of the said guide forming a stationary member of two cutting members, an oscillatable cutting member pivoted to a support adjacent the first cutting member 30 having a cutting edge, which when said second cutting member oscillates moves in a plane at right angles to the projecting portion of the wire between the end of the guide and the arbor, a reciprocable slide adapted to bend upon the arbor the projecting portion of the wire after it has been severed, and a cam connected with the said slide and moving therewith, which engages said pivoted cutter to oscillate the same on its pivot at a predetermined point in the movement of the slide and cause said cutter to engage the wire, and by cooperation with the said fixed cutter to sever the said projecting portion of the wire while it lies on the arbor.
2. In a machine of the character described, an arbor, a reciprocable slide adapted to bend a wire blank over the arbor to form a staple, a cutting member adjacent the arbor 50 which aids in supporting the wire, a pivoted cutting member adapted to cooperate with said first cutter, and a cam on said slide member which actuates said pivoted cutter to sever the portion of the wire which is to form the blank at a predetermined time in relation to the bending operation of the slide upon the blank, and a spring for restoring the said pivoted cutting member to its position preliminary to another cutting operation.
3. In a machine of the character described, an arbor, a wire guide adjacent the arbor through which wire is fed to lay upon the arbor a projecting portion of the wire, the forward end of the said guide forming one 60 member of two cutting members, a reciprocable slide adapted to bend the wire upon the arbor to form a staple, a second cutting member pivoted to a support adjacent the first cutting member, and a cam connected with the slide and moving therewith which actuates the said pivoted cutter to oscillate the same on its pivot at a predetermined point in the movement of the slide with relation to the arbor so as to sever the projecting portion of the wire which is to form the blank while it lies on the arbor.
4. In a machine of the character described, an arbor, a wire guide adjacent the arbor through which wire is fed to lay upon the arbor a projecting portion of the wire, the forward end of the said guide forming one 70 member of two cutting members, a reciprocable slide adapted to bend the wire upon the arbor to form a staple, a second cutting member pivoted to a projection on said wire guide, and a cam connected with the slide and moving therewith which actuates the said pivoted cutter to oscillate the same on its pivot at a predetermined point in the movement of the slide with relation to the arbor so as to sever the projecting portion of the wire which is to form the blank while it lies on the arbor.
5. In a machine of the character described, an arbor, a wire guide adjacent the arbor through which wire is fed to lay upon the arbor a projecting portion of the wire, the forward end of the said guide forming a stationary member of two cutting members, 80 an oscillatable cutting member pivoted to a support adjacent the first cutting member having a cutting edge, which, when said second cutting member oscillates, moves in a plane at right angles to the projecting portion of the wire between the end of the guide and the arbor, a reciprocable slide, means for actuating said slide to engage the projecting portion of the wire while it lies upon the arbor, and a cam connected with the said slide and moving therewith which engages said pivoted cutter to oscillate the same on its pivot at a predetermined point in the movement of the slide and cause said cutter to engage the wire and by cooperation with the said fixed cutter to sever the said projecting portion of the wire while it lies on the arbor, the continued movement of the slide bending the severed blank over the arbor.
6. In a machine of the character described, an arbor, an apertured wire guide adjacent the arbor through which the wire is fed to lay upon the arbor a projecting portion of the wire, the forward end of the said guide forming one 90 member of two cutting members, an oscillatable cutting member pivoted to a support adjacent said first cutting member and having a cutting edge, which, when said second cutting member oscillates, engages 100

the projecting portion of the wire between the end of the guide and the arbor, a reciprocal slide, means for actuating said slide to engage the projecting portion of the 5 wire while it lies upon the arbor, a cam mounted upon said slide and moving therewith, a spring which normally retains said oscillatable cutter in position to be engaged by the cam during the descent of the slide, 10 the continued descent of the slide causing the cam to turn the oscillatable cutter on its

pivot to engage the wire where it projects from the guide and to sever the said projecting portion of the wire while it lies on the arbor, said spring operating to restore 15 the said oscillatable cutter to its normal position after the cam has been released from the cutter on the return movement of the slide.

In testimony whereof I affix my signature.

GEORGE W. PERKINS.
